PORTABLE GUN BORE CLEANER

Donald F. Goodwin, Mayfield Heights, and John X. Sopkovick, Cleveland, Ohio

Application November 23, 1953, Serial No. 393,621

7 Claims. (Cl. 15—104.165)

This invention relates to improvements in a cleaning implement and more particularly to a portable gun bore cleaner.

One of the objects of the present invention is to provide a gun bore cleaner easily carried by the hunter in the field so that he can easily and quickly remove barrel obstructions and clean the barrel bore whenever necessary.

A further object of the present invention is to provide a gun barrel bore cleaner having an elongated body substantially unyielding in at least one axial direction so that it can assume a straight end to end position when used for barrel cleaning and with said body also being laterally bendable for coiling into a compact form for carrying.

A further object of the present invention is to provide a gun barrel bore cleaner, as set forth in the preceding paragraph, wherein one end of said elongated body has a barrel cleaning member coactable with the other end for securing the opposite ends together when in coiled position for convenient carrying.

A further object of the present invention is to provide a gun barrel bore cleaner characterized by its structural simplicity, economy of manufacture, ease of assembly of its parts, strong and sturdy nature, and adaptability for use under many conditions.

Other features of this invention reside in the arrangement and design of the parts for carrying out their appropriate functions.

Other objects and advantages of this invention will be apparent from the accompanying drawings and description and the essential features will be set forth in the appended claims.

In the drawings,

Fig. 1 is a side elevational view of the gun barrel bore cleaner of this invention when assuming a straight end to end position for use as a barrel cleaner;

Fig. 2 is a side elevational view of the gun barrel bore cleaner coiled into a compact form for carrying with the ends detachably connected together and with convenient carrying pouch dot-dashed around it within which the cleaner may be carried; while

Fig. 3 is an enlarged view of a modified form of barrel cleaning member for the right hand side of Fig. 1 showing the member and spring in position for assembly.

Before the barrel bore cleaner here illustrated in specifically described, it is to be understood that the invention herein involved is not limited to the structural details or arrangement of parts here shown since structures embodying the present invention may take various forms. Also, it is to be understood that the phraseology or terminology herein employed is for purposes of description and not of limitation since the scope of the present invention is denoted by the appended claims.

Those familiar with this art will recognize that this invention may be applied in many ways, but we have chosen to illustrate the same as a gun barrel bore cleaner of portable form readily usable for cleaning the barrel

2

bore of a rifle, shotgun, pistol, revolver, or other firearm.

Although the sportman's firearm is generally cleaned only at home or in the hunting camp and not in the field during hunting, it sometimes becomes desirable and absolutely necessary to clean the gun barrel bore in the field far from camp and home. If the barrel bore becomes clogged with mud or snow during hunting, the hunter must remove this obstruction from the barrel bore. If he attempts to shoot the gun with the obstruction in the barrel, the breech pressure will be raised to an exceedingly large amount and there is always the danger of blowing up the gun barrel or breech mechanism with resulting serious injury to the hunter. Frequently the hunter is many miles from camp when the barrel bore gets its obstruction, and it is not convenient or expeditious for him to return back to his base camp for the sole purpose of cleaning the barrel bore. A rigid cleaning rod, sufficiently long to clean either a rifle or shotgun, can present a very difficult problem because it is long, stiff and awkward to carry. The present invention solves this problem by providing a gun barrel bore cleaner of a portable and compact nature readily and easily carried by the hunter in his hunting coat and always ready for instant use whenever the need occurs.

25 The gun barrel bore cleaner includes a body means or member 10 capable of assuming a straight end to end position, as shown in Fig. 1, when used for barrel cleaning. This is disclosed in the present invention as being an elongated helical spring having a right hand helix. However, any elongated body means may be suitable if it is substantially unyielding in at least one axial direction and is laterally bendable for coiling. For example, a flexible shaft would be satisfactory. This axial rigidity permits the spring 10 to act as a cleaning rod in being pushed through or pulled through the gun barrel bore since the spring has sufficient stiffness. Also, the outside diameter of the spring 10 may be designed to be only slightly smaller than the barrel bore so that when it is pushed through the gun barrel bore, it will receive lateral support from the barrel bore. However, the spring may have sufficient strength so that even though its outside diameter is substantially smaller than the barrel bore, it will have sufficient stiffness for cleaning when pushed through the barrel bore.

30 45 One or both ends of the spring or body means 10 has a member connected thereto, either in the form of a complete barrel cleaning member, such as a brush, or in the form of a member constructed to serve as at least a portion of a barrel cleaning member, such as an eye or enlarged head on an axially extending cylindrical portion for receiving a cleaning patch in a conventional manner through the eye or over the head. Although various types of barrel cleaning members could be used, we have chosen to attach a cleaning patch tip or tip patch cleaner 11 to one end and a wire bristle cleaning brush 12 to the other end.

50 55 The member 11 of the barrel cleaning member on one end has an eye 11a therein formed as an elongated aperture in the present disclosure. When the cleaner is being used by pulling through the barrel, a piece of cleaning cloth or other material may be threaded through this eye 11a. When the cleaner is being used for push-through cleaning, the cleaning cloth can be threaded through the eye in the same manner or a circular cleaning patch can be placed over the right end of the member 11 with both being telescoped through the barrel by moving the cleaner toward the right in Fig. 1.

60 65 70 A wire bristle cleaning brush 12, forming the barrel cleaning member on the other end, is manufactured by twisting two wires 12a, 12b helically together with wire bristles 12c extending laterally therebetween so that in

the resulting brush the bristles have the helical form shown in the drawings.

These members 11 and 12 on opposite ends of the spring 10 serve another function in addition to the cleaning function when the spring 10 is in its straight end to end position in Fig. 1. Since the spring is laterally bendable, the spring may be coiled into a compact form for carrying. However, it is desirable to have means provided on the cleaner for detachably connecting together the opposite ends thereof so that the cleaner not only will form a compact package for carrying but also prevent the danger of having the end flung dangerously outwardly by the release of the spring. This latter action would not only prevent convenient carrying but also subject the hunter to the danger of physical harm by the spring driven members 11 and 12. Therefore, after the spring 10 has been coiled together, the ends thereof are wrapped around or interlocked with the coiled form, and then the ends of the members are detachably connected together to assume the Fig. 2 position for convenient and safe carrying in the field until barrel cleaning is required.

The ends are detachably but firmly secured together by eye 11a of member 11 and any eye engageable portion on the opposite end of spring 10, such as a hook or even an elongated portion like a length of wire or a cylindrical cleaning tip with an enlarged head, as brought out in more detail in the next paragraph. In the present disclosure, this portion is located on the outer end of the brush 12. Here, the component wires 12a and 12b of the brush are formed from a single length of wire twisted upon itself with an end loop 12c being integrally formed at the outer end thereof. A portion 12d is notched out of this loop so that it forms a resulting hook for detachable engagement with the eye 11a.

However, this portion need not be formed by a clearly bent hook on the end of the barrel brush member 12. For example, the left end of the spring 10 in Fig. 1 may have a projection thereon detachably engageable with the eye 11a so that the cleaner has only the one member 11 thereon for barrel cleaning. Alternatively, the member 11 may be omitted and the eye or a suitable hook may be formed from the last coil of the spring 10 on the right-hand side thereof for detachable engagement with the portion on the end of the brush. Also, if the neck of member 11 between eye 11a and threads 11b or the neck behind the enlarged head on the other type patch cleaner is sufficiently small in diameter, it may be inserted through gap 12d into hook engagement; also, if the enlarged end is sufficiently small on any of these type patch holders, it may be inserted into the bore of loop 12c even though notch 12d has not been cut. Also, the portion on the end of the brush need not be bent into a clear hook shape. For example, one or both of the wires 12a, 12b may extend axially and straight beyond the end of the brush bristles 12e to form a portion detachably engageable with the eye 11a and held in position by the resilient spring 10 tending to uncoil the cleaner from the Fig. 2 to the Fig. 1 position. Many other forms of this invention will be readily apparent to anyone skilled in the art and it should be clearly understood that any form of member, serving as at least a portion of a barrel cleaning member could be used at each end of the spring 10 but we prefer and have found most satisfactory results obtainable with the structure disclosed herein. Also, the cleaning patch may be held in any suitable structure during rifle cleaning, whether it be eye 11a, hook 12c or an eye or loop formed by wire 12c without notch 12d.

After the cleaner has assumed the position in Fig. 2, it should be readily understood that the whole unit can be put into a pouch 13 being formed of cloth, plastic, or other suitable material and having an envelope portion 13a closed except for an open top which may be closed by a bendable flap 13b and then locked in position by a snap fastener 13c being connected to the front wall

of the envelope 13a. This pouch 13 may be easily carried in the pockets during hunting.

If desired, a detachable clip can be wrapped around the coils of spring 10 at the upper right in Fig. 2, opposite the bore cleaning members 11 and 12, but we have found that this is not necessary when the members are properly formed for the detachable engagement of the opposite ends of the gun barrel cleaner.

Whenever the rifle or shotgun bore becomes obstructed in the field, the hunter can quickly and easily remove the pouch 13 from his pocket, remove the gun barrel cleaner from the pouch, detach hook 12c from eye 11a, unwind the interlocked ends of the spring 10 and then carefully uncoil the spring so that the gun barrel can be readily used by either pushing through or pulling through the gun barrel bore. The cleaner assumes a straight end to end position, as shown in Fig. 1, but either the barrel cleaning brush member 12 or the member 11, adapted to carry a cleaning patch for barrel cleaning, is readily usable for cleaning the barrel. Spring 10 is substantially unyieldable in at least one axial direction and preferably in both axial directions so that it will have sufficient stiffness for the cleaning operation. When the hunter is finished cleaning his gun, he merely reverses the above-mentioned operation and then inserts pouch 13 in his pocket for convenient carrying while he continues the hunt.

It has been found desirable to quickly and efficiently attach the members 11 and 12 to the opposite ends of spring 10 in an inexpensive manner. Both of the members have identical male threads formed on the spring end thereof with member 11 having threads 11b formed integrally thereon while brush 12 has an adaptor 15 with male threads 15a on one end and a sleeve 15b on the other end telescoped over and secured to the end of the twisted wires 12a, 12b.

Since both threads 11b and 15a are identical, only one need be described, for example threads 11b. The thread has for proper interlock the same hand as the spring helix, in other words, the helix of the spring and the helix of the threads are both advancing in the same direction. The inside diameter of the spring is approximately 0.004-0.005 inch larger than the outside diameter of the thread. The thread 11b is telescoped into the bore of the spring 10 within a half spring coil short of the end of the thread. Then, the unit is heated to about 480° Fahrenheit for about twenty minutes so that the steel spring will creep forwardly to its finished position at the end of the thread and then will firmly grip the thread so that the member 11 is not easily removed therefrom. It is frequently necessary to use a spanner wrench or equivalent to remove each member from its securing engagement with the bore of spring 10. Although other methods of manufacture may be used, we have found this to be the preferred method.

This gun barrel cleaner can of course be made in different outside diameters so that each one will be especially designed for one particular rifle caliber, shotgun gauge, or other fire arm bore size.

Also, a modified form of member 11 may be used. The member 11 in Fig. 1 is machined from a solid piece of stock pierced to form the eye while the modified form of member 11' in Fig. 3 is formed from one continuous and integral length of spring wire wound into the form of a spring 11b' with the right end thereof extended toward the right and bent back on itself to form eye 11a' with its distal end extending between spring coils 11b'. This member 11' is usable in the same manner as a cleaning patch tip or tip patch cleaner. Also, the spring 11b' forms a thread on its periphery with the same hand as the helix of spring 10 with an outside diameter substantially the same as thread 11b. Hence spring 11b' can in the same manner be threaded in the direction of the arrows into the bore of spring 10 and heated to cause creeping to secure the parts together.

Various changes in details and arrangement of parts can be made by one skilled in the art without departing from either the spirit of this invention or the scope of the appended claims.

What we claim is:

1. A gun barrel cleaner comprising an elongated body means substantially unyielding in at least one axial direction and laterally bendable for coiling, a member on one end having an eye, and a barrel cleaning brush member on the other end being formed by twisting two wires helically with bristles extending laterally therebetween, the end of said wires extending beyond the end of the bristles and forming a portion for detachably engaging with said eye carrying member, whereby said cleaner may either assume a straight end to end position when used for barrel cleaning or be coiled, when not in use, into a compact form for carrying with the ends detachably connected together.

2. A gun barrel cleaner comprising an elongated body means substantially unyielding in at least one axial direction and laterally bendable for coiling, a member on one end having an eye, and a barrel cleaning brush member on the other end being formed by twisting two wires helically with bristles extending laterally therebetween, the end of at least one of said wires extending beyond the end of the bristles being bent into the form of a hook to detachably engage in said eye, whereby said cleaner may either assume a straight end to end position when used for barrel cleaning or be coiled, when not in use, into a compact form for carrying with the ends detachably connected together.

3. A gun barrel cleaner comprising an elongated body means substantially unyielding in at least one axial direction and laterally bendable for coiling, a member on one end having an eye, and a barrel cleaning brush member on the other end being formed by twisting two overlapped portions of a single wire helically with bristles extending laterally therebetween, the interconnected ends of said wire portions extending beyond the end of the bristles being integrally connected to form a loop, a portion of said loop being notched out to make the two wire portions two separate wires and to form a hook to detachably engage in said eye, whereby said cleaner may either assume a straight end to end position when used for barrel cleaning or be coiled, when not in use, into a compact form for carrying with the ends detachably connected together.

4. A gun barrel cleaner comprising an elongated helical spring substantially unyielding in at least one axial direction and laterally bendable for coiling, a member on one end having an eye, and a barrel cleaning brush member on the other end being formed by twisting two wires helically with bristles extending laterally therebetween, the end of said wires extending beyond the end of the bristles and forming a portion for detachably engaging in said eye, both of said members having threads of the same hand as the spring helix and tightly interlocked therewith to securely lock each member to one end of said spring, whereby said cleaner may either assume a straight end to end position when used for barrel cleaning or be coiled, when not in use, into a compact form for carrying with the ends detachably connected together.

5. A gun cleaner comprising an elongated body means having opposite ends and substantially unyielding in at least one axial direction with said opposite ends detached for gun cleaning and laterally bendable for coil-

ing when not in use, a first member on one end, a second member on the other end having a hook portion for detachably connecting in hooking engagement with said first member so that said cleaner may either assume a straight end to end position when used for barrel cleaning or to be coiled, when not in use, into a compact form for carrying with the ends detachably hooked together, at least one of said members being constructed to carry a cleaning patch, said first member being said one member and having an eye for receiving said cleaning patch and for engagement with said hook for said hooking engagement when not in use, said body means being an elongated helical spring, said first member being formed from a single length of bent wire separate from said spring and said second member and bent at its outer end into said eye and bent at its inner end into a helix of the same hand as said spring helix and detachably screwed into the bore of said spring to detachably lock with the helix thereof.

20 6. A gun cleaner comprising an elongated body means having opposite ends and substantially unyielding in at least one axial direction with said opposite ends detached for gun cleaning and laterally bendable for coiling when not in use, a first member on one end, a second member on the other end having a hook portion for detachably connecting in hooking engagement with said first member so that said cleaner may either assume a straight end to end position when used for barrel cleaning or be coiled, when not in use, into a compact form for carrying with the ends detachably hooked together, at least one of said members being constructed to carry a cleaning patch, said body means being an elongated helical spring, said one member being a solid member pierced at its outer end to provide an eye for receiving said cleaning patch and having threads at its inner end of the same hand as the helix of said spring and detachably screwed into the bore of said spring to detachably lock with the helix thereof.

25 7. A gun barrel cleaner comprising an elongated helical spring with a right hand helix, a member separate from said spring constructed to serve as at least a portion of a barrel cleaning member detachably connected thereto on one end, said member having a threaded end with a right hand thread interlocked with said spring helix, said member having an eye with said member and eye formed from a single length of bent wire terminating at the end remote from its thread outwardly beyond the inner end of its thread.
